UNITED STATES PATENT OFFICE.

ISIDOR KITSEE, OF PHILADELPHIA, PENNSYLVANIA.

TELEGRAPHIC TRANSMITTING DEVICE.

No. 831,355.

Specification of Letters Patent.

Patented Sept. 18, 1906.

Application filed June 21, 1906. Serial No. 322,725.

To all whom it may concern:

Be it known that I, ISIDOR KITSEE, a citizen of the United States, residing at Philadelphia, in the county of Philadelphia and 5 State of Pennsylvania, have invented certain new and useful Improvements in Telegraphic Transmitting Devices, of which the following is a specification.

My invention relates to an improvement in 10 telegraphic transmitting devices. Its object is to produce a device efficient to transmit reversals over a line of transmission.

To-day it is a well-established fact that 15 over lines with great capacity, such as subterranean or submarine cables, telegraphing with true reversals is desirable. In such transmission the use of a single Morse key with a single contact is preferred before the 20 complicated double-key arrangement of submarine cables, and I have illustrated in the accompanying drawing the preferred arrangement of accomplishing this object.

In the drawing, which in diagrammatic view illustrates my invention, 1 1 are the 25 line-wires, 2 3 are two sources of current, here shown as batteries, the source 2 comprising here four cells and the source 3 comprising two cells, both of these sources connected in opposition as to each other. 6 is 30 a condenser, here inserted between the two sources. 5 is an inductive resistance shunted by the condenser 4. 7 is the lever of a common Morse key, and 8 the stationary point of same. Normally—that is, when the line is 35 idle—the key is open, and as the force of the battery 2 is greater than the force of the battery 3 an impulse will flow over the line in the direction of the unfeathered arrow; but when the key is depressed, thereby shunting 40 the battery 2, the force of the battery 3 is unopposed, and an impulse will flow over the line in the direction of the feathered arrow. The operator in sending impulses over the line manipulates his key in the usual manner. It is obvious that at the receiving-station a polarized receiver has to be used. I 45 have not illustrated this device, as my invention only pertains to the transmitting of true reversals. In the manipulation of the arrangement as illustrated, the great disadvantage arose that on lines of great length a large number of batteries has to be used, and in the act of closing the key one of these sets of batteries has to be short-circuited, and in 50 practice the deterioration of the battery was considered.

In my experiments I have found that an inductive resistance, such as an electromagnet, placed in series with the line and in the region of the shunt does not in the least decrease the value of the reversals through the manipulation of the key. In fact, this value is to a slight extent increased. I have manipulated the key of a device such as described on a line having about ten thousand ohms resistance, and I placed in the region of the shunt an electromagnet of five thousand ohms and forty-four henries, and the measurement showed me an increase of the available energy over an arrangement wherein the inductive resistance was replaced by a non-inductive resistance.

I made different tests over different lines, changing the value of the resistance from five ohms up to one hundred thousand, and every one of these tests proved the efficiency of the inductive resistance. The only drawback was that when the key was open and an impulse traveled over the line from the other terminal the inductive resistance, if of high value, retarded the flow of this impulse, and I therefore have recourse to static means, such as a condenser, shunting or overbridging the coil proper. With this arrangement telegraphing with true reversals with the aid 85 of a common Morse key can easily be accomplished, no matter how large the number of cells which have to be shunted with the aid of this key.

Having now described my invention, what I claim as new, and desire to secure by Letters Patent, is—

1. In telegraphy, a transmitting device embracing two sources of current of unequal force connected in opposition as to the line, a transmitting-key adapted to shunt one of said sources and an inductive resistance in the region of said shunt.

2. A telegraphic transmitting device comprising two unequal sources of current connected in series as to the line and in opposition as to each other, a transmitting-key adapted to shunt one of said sources and a resistance and static means in the region of said shunt.

3. In telegraphy, means to transmit true reversals, said means embracing two sources of current of unequal force and connected in series to the line and in opposition as to each other, a transmitting-key adapted to shunt one of said sources and inductive resistance adapted to lessen the short-circuiting of said source.

4. In telegraphy, means to transmit reversals, said means embracing two sources of current of unequal force and in opposition as to each other, but in series to the line and 5 means to shunt one of said sources and also embracing means in the region of said shunt to prevent undue deterioration of said source and static means overbridging said first means.
- 10 5. In combination with a line of transmission two sources of current connected in series as to the line and in opposition as to each other, shunt for one of said sources, an electromagnet in the region of said shunt, and 15 means to open and close the shunt around one of said sources and said electromagnet.
6. In telegraphy, means to transmit true reversals, said means embracing two sources of current of unequal force connected in opposition as to each other and inserted in the 20 line of transmission, a sending-key and means to shunt therewith one of said sources, in combination with an inductive resistance in the region of said source and a condenser shunting said inductive resistance. 25

In testimony whereof I affix my signature in presence of two witnesses.
